UNITED STATES PATENT OFFICE.

WILLIAM ZULCH, OF COBLESKILL, NEW YORK.

SILO-HOOP TIGHTENER.

1,388,012.

Specification of Letters Patent. Patented Aug. 16, 1921.

Application filed December 1, 1920. Serial No. 427,551.

To all whom it may concern:

Be it known that I, WILLIAM ZULCH, a citizen of the United States, and a resident of Cobleskill, county of Schoharie, and 5 State of New York, have invented a new and Improved Silo-Hoop Tightener, of which the following is a full, clear, and exact description.

This invention relates to improvements 10 in silo hoop tighteners, an object of the invention being to provide a device of this character which will serve the double purpose of a tightener and a ladder.

A further object is to provide a hoop 15 tightener which will be comparatively easy to install on ordinary silo hoops, and one which may be operated with facility.

A still further object is to provide a device of the character stated which will be 20 simple and practical in construction, strong and durable in use, and comparatively inexpensive to manufacture.

Although the device is primarily intended 25 for use on silos, it is not limited to this particular use but may be utilized successfully on vats or similar types of containers which employ hoops.

With these and other objects in view, the 30 invention consists in certain novel features of construction and combinations and arrangements of parts as will be more fully hereinafter described and pointed out in the claims.

In the accompanying drawings:

35 Figure 1 is a fragmentary view in transverse section through a silo, illustrating my improved tightener in operative position, with parts broken away for clearness.

Fig. 2 is a plan view or front elevation of 40 my improved tightening mechanism.

Fig. 3 is a sectional view on the line 3—3 of Fig. 1.

1, 1 represent two upright staves of a silo. These particular staves are located one on 45 each side of a door opening. 2 represents a bracing rod extending transversely across the door opening, and having its threaded ends 3 embedded in the staves. Gaskets 4 and lock nuts 5 around the threaded ends of 50 the rod space the two staves apart and prevent tightening of the hoop 6 from altering the shape of the door opening.

Pairs of tapered channel guide blocks 7, 55 preferably of metal, are secured to the staves on each side of the door opening. The pairs of blocks are formed with oppositely dis-

posed dovetailed grooves 8. The taper of the blocks 7 is somewhat exaggerated on the drawing, but it is to be understood that the outer face 9 of the blocks is disposed tangentially to the walls of the silo, and the inner face of the blocks is positioned against the walls. Any suitable securing device such as 10 may be employed to fasten the blocks to the silo. 60

The hoops 6 are preferably in the form of wire cables having their ends fastened to metal plates 11. The plates 11 are formed with tenons 12 slidable in the grooves 8. Sufficient space is left between 70 the blocks 7 for the accommodation of a U-bolt 13 which has its threaded extremities 15 projecting through the plate 11 and receiving nuts 14 which are adjustable to securely clamp or squeeze the ends of the 75 cable 6 between the intermediate portion of bolts and the plates 11. 65

The plates 11 are integral with flanges 16 disposed at right angles to the plates, and formed with alined openings for the 80 reception of a rod 17. The threaded ends 18 of the rod 17 project through the openings in the flanges and receive adjusting nuts 19 which confine the flanges between them. 85

These rods 17 located one above the other, on the respective hoops of the silo, form a convenient ladder for the use of one who desires to inspect the contents of the silo from one of the door openings. 90

The operation will be readily understood. When it is desired to tighten the hoops it is merely necessary to tighten the nuts 19 or move them toward each other on the rod 17. These nuts through the medium of the 95 flanges 16 will pull the plates toward one another, the plates sliding in the dovetailed channels between the blocks 7, and since the ends of the hoop are secured to the plates 11, this movement of the plates necessarily 100 tightens the hoops about the silo.

Various slight changes and alterations might be made in the general form of the parts described without departing from my invention, and hence I do not wish to limit 105 myself to the precise details set forth, but shall consider myself at liberty to make such slight changes and alterations as fairly fall within the spirit and scope of the appended claims.

Inasmuch as the rods 17 serve as the steps 110 of a ladder, one using the ladder will know

that a loose step means a loose hoop which needs to be tightened. If the rod 17 should not provide sufficient adjusting means, the U-bolts 13 may of course be used for taking 5 in some of the cable.

What I claim is:

1. The combination with an annular body and a flexible device encircling the body, of pairs of channel guide blocks spaced 10 apart and secured to the outer face of the body, plates slidable in the guide blocks and connected to the ends of the flexible device, and means for moving the plates in opposite directions.
- 15 2. The combination with an annular body and a flexible device encircling the body, of pairs of channel guide blocks spaced apart and secured to the outer face of the body, plates slidable in the guide blocks and connected to the ends of the flexible device, and means for positively moving the plates toward each other.
- 20 3. The combination with an annular body and a flexible device encircling the body, of pairs of channel guide blocks spaced apart 25 and secured to the outer face of the body, plates slidable in the guide blocks and connected to the ends of the flexible device, and means for positively moving the plates toward each other, said means comprising a pair of flanges on the guide blocks having aligned openings therein, a threaded rod located through said openings, and adjusting nuts on the ends of the rod confining the 30 flanges between them.
- 35 4. The combination with a silo having a door opening therein and bracing rods located transversely of said opening, of a flexible hoop encircling the silo, pairs of 40 tapered channel guide blocks located on

each side of the openings, said blocks having their inner faces located against the wall of the silo and their outer faces located in the same vertical plane, plates slidable between the channel guide blocks, flanges 45 on the plates having aligned openings therein, a rod positioned through the openings, the ends of said rod being threaded, adjusting nuts around the threaded ends of the rod confining the flanges between them and 50 adapted to move the plates in opposite directions, and means securing the ends of the flexible hoop to the plates.

5. The combination with a silo having a door opening therein and bracing rods located transversely of said opening, of a flexible hoop encircling the silo, pairs of tapered channel guide blocks located on each side of the openings, said blocks having their inner faces located against the 60 wall of the silo and their outer faces located in the same vertical plane, plates slidable between the channel guide blocks, flanges on the plates having aligned openings therein, a rod positioned through the openings, 65 the ends of said rod being threaded, adjusting nuts around the threaded ends of the rod confining the flanges between them and adapted to move the plates in opposite directions, and means securing the ends of the 70 flexible hoop to the plates, said means comprising U-bolts having their threaded extremities extending through the outer faces of the plates, intermediate portions encircling the ends of the hoops, and adjusting 75 nuts on the free ends of the U-bolts controlling the binding action of their intermediate portions on the ends of the hoop.

WILLIAM ZULCH.
